UNITED STATES PATENT OFFICE.

WILLIAM K. JENNE, OF ILION, NEW YORK, ASSIGNOR TO THE WYCKOFF, SEAMANS & BENEDICT, OF SAME PLACE.

TYPE-WRITING MACHINE.

SPECIFICATION forming part of Letters Patent No. 596,371, dated December 28, 1897.

Application filed June 23, 1879. (No model.)

To all whom it may concern:

Be it known that I, WILLIAM K. JENNE, a citizen of the United States, residing at Ilion, in the county of Herkimer and State of New York, have invented certain new and useful Improvements in Type-Writing Machines, of which the following is a specification.

My invention relates to type-writing machines; and it consists in various features, de-
tails, and combinations hereinafter set forth.

In the accompanying drawings, Figure 1 is a perspective view of a type-writer embodying my invention; and Figs. 2 to 12, inclusive, views illustrating various details and herein-
after referred to in connection with the de-
scription of said parts.

The improvements pertain more particu-
larly to type-writers in which two printing-
characters are carried by a single type-bar
and in which the platen or paper roll is for
that reason made movable laterally or at right
angles to its axis in order to bring it properly
over one or the other printing-character.

In the drawings, A indicates the frame of
the machine, comprising a rectangular base,
a series of posts or uprights, and a top plate,
which latter is formed with a large central
opening B.

At or near its rear side the base of the frame
A is provided with a depending rib C³, Fig.
12, which extending across the base from side
to side forms a fulcrum for a series of finger-
key levers C of the second order, as shown in
Fig. 12.

Each finger-key lever C is connected by a
link C⁴ with one or another of a series of type-
bars B, which are levers of the first order,
having one quite short arm, to which the links
are attached, and a long arm, at the outer
extremity of which is placed the double print-
ing character or type, as heretofore. The
type-bars are carried in suitable hangers
grouped in circular series around the open-
ing B.

Depending from the top plate of frame A,
near its rear, is a hanger-plate A², in which is
pivotally supported an oscillating elbow-lever
G², the upright arm or member of which car-
ries the usual letter-space dogs, while from
the forwardly-projecting horizontal member
thereof is suspended a bar G, commonly

called the "universal" bar, which passes be-
neath and rests against the under side of the
finger-key levers C. From this arrangement
it follows that the depression of any finger-
key lever will cause the rocking of the oscil-
lating frame G², moving the rigid letter-space
dog into and the yielding letter-space dog out
of alignment with the letter-space rack-bar,
as usual.

Upon referring to Fig. 12 it will be seen
that the fulcrums of the finger-key levers C
are at one end of said levers and the finger-
buttons C² are at the opposite ends, and it
will also be observed that universal bar G
and oscillating letter-space frame or lever G²
are located between the fulcrum-rib C³ and
the connections of the links C⁴ with the finger-
key levers. The finger-buttons C² are
arranged in rows or tiers at different dis-
tances from the fulcrum-rib C³; but the lever-
age is made practically uniform by properly
locating the attachments connecting the links
C⁴ with the key-levers C, as indicated in Fig.
1. The oscillating lever or frame G² is nor-
mally pressed back by a spring, as usual, this
and various other details being omitted from
the drawings because of ordinary construc-
tion and arrangement.

The top plate of the frame A is formed with
lateral arms or extensions, from which rise
standards or ears, by which are supported the
ends of a rod A³, as shown in Fig. 1. This rod
is of the form in cross-section shown in Fig.
3—that is to say, its front and rear faces are
beveled or inclined toward each other from
about the horizontal plane of its axis upward,
a narrow flattened space being left between
the beveled faces at the upper side.

The rod or rail A³ is designed to support the
rear side of a traveling paper-carriage L,
which is formed with perforate ears to loosely
encircle said rod and is furnished with rollers
L², V-grooved, as in Fig. 3. The walls of the
grooves of rollers L² have the same inclination
as the beveled faces of rod or rail A³, but the
groove is of such depth that its bottom does
not make contact with the crest of rod or rail
A³. From this it will be seen that the rollers
seat themselves closely and firmly upon the
guide rod or rail and preclude lateral play be-
tween the parts, thus insuring a straight and

steady travel of the carriage and consequent good alinement of the printing.

The carriage L is supported at its front by a roller L, which runs upon the upper face of 5 the top plate of frame A.

As mentioned, the paper roll or platen requires to be shifted bodily at right angles to the line of travel of the carriage to bring the printing-point over one or the other of the

10 two printing-characters of a type-bar, and to accomplish this readily and insure accuracy of adjustment I adopt the construction illustrated in Figs. 1, 4, and 7. In these figures N N indicate two slides, respectively fitted to 15 the end bars of the frame or carriage L and free to slide thereon. The slides N N move in the direction of their length toward and from the front and rear of the machine, the keyboard being regarded as the front.

20 The slides N N are connected by a rod R², seated at its ends in blocks or lugs R, and each slide is formed or furnished with two upright ears or standards N' and N³. The ears N' serve to sustain the journals of the platen- 25 roll Q, and to each ear N³ is pivoted a triangular block O³, the two blocks being connected at their upper ends by a rod P, as shown in Fig. 1. From the rod P a flat bar P' extends forward and downward, its end being carried 30 through a guide P² on the front bar of the frame of carriage L, Fig. 1.

From the guide-bar P a rod or stem P¹² extends downward to a point slightly above the top plate of the frame, where it terminates 35 in a crotch or yoke P³.

P⁴ indicates a cylindrical rod carried above the top plate of the machine by the upper arms of two elbow-levers P⁵, rigidly secured upon a common shaft P⁶, carried in hangers 40 or bearings beneath the top plate. The elbow-levers P⁵ have their lower arms arranged to project in opposite directions from the shaft P⁶, as shown in Fig. 1, one toward the front and the other toward the rear of the machine, and each is connected by a link P⁷ with a shift-key lever specially provided for it.

By reason of the arrangement just described it will be seen depression of the shift-key lever connected with one of the levers P⁵ will 50 move rod P⁴ rearwardly, while depression of the shift-key lever attached to the other will move said rod forwardly. The yoke or crotch P³ straddles rod P⁴ and moving therewith carries the slide P' and the rod P with it, the effect of which is that the blocks O³ are rocked upon their pivots as far as they are free to go and then are moved bodily, carrying with them the slides N N and the parts mounted thereon.

60 Each slide N is formed with a slot N², through each of which slots project two short studs or posts M² M³, located at such distance apart as to allow a limited play of the slides N before the end walls of the slots bear against 65 said studs or posts.

Each block O³ has pivoted to it two hooks or dogs O O, the free ends of which project

in opposite directions, as shown in Figs. 1 and 4. These hooks rest upon short studs O⁴, projecting from the face of each block O³ 70 when the blocks are in a medial or upright position; but when the blocks are tipped, as in Fig. 4, one hook is lifted up and the other is permitted to descend, as indicated, the free hook being always on the advancing side of 75 block O³ and of rod P⁴.

The purpose of the hooks is to engage one or the other of the posts M² and to lock the shifting carriage N N R² in one or the other of its two positions, the free hook riding over 80 and engaging with the outer face of the post or stud, as shown in Fig. 4.

It will be observed that the mere depression of the appropriate finger-shift-key lever rocks the levers P⁵, moves slide P', rocks the 85 blocks O³, lifts one set of hooks O and disengages them from their studs or posts M², moves the slides N N with the platen-roll and attendant parts rearward or forward, as the case may be, and carries the other pair of 90 hooks O over and into locking engagement with the second set of studs. In this way the platen is not only quickly shifted, but its movement is accurately determined by the length of the slots and it is firmly locked in 95 position, thus insuring proper alinement and clean unblurred printing.

In order that the movements of the supplemental carriage or shifting platen-frame N N R² may be free and easily effected, the end 100 bars of the carriage-frame L are provided with rollers M, the peripheries of which project very slightly above said end bars and sustain the slides N N, as shown in Figs. 1 and 4 and indicated by dotted lines in Fig. 7. This provision enables the operator to shift the platen through the expenditure of little or no more force than is required to actuate one of the type-bars, which is a matter of importance, greatly facilitating the rapid operation of the 105 machine.

Fig. 6 shows the underside of one end of the shifting carriage and parts carried thereby.

Q is the platen or paper roll, and R² the rod connecting the slides N N. 115

W is the reversed scale, and S' is a roller which presses the paper against the platen or paper roll.

The roller S' has the ends of its shaft S³ or axle carried in slots N⁴ in the slides N, in which slots it has a limited play toward and from the platen. It is furnished at its ends with pulleys S², one of which is shown in Fig. 6. The rod R² also carries two loose pulleys S², about which pass rubber bands S, which, passing beneath the platen, are also carried about the pulleys S² on the ends of roller S'. The upper folds of the bands S bear against the platen or against the paper thereon, and hold it to the platen, while the lower folds or 120 lengths of said bands pass clear of the upper folds and thus avoid friction or retardation. 125

To protect the bands S, there is provided for each a shield-plate V, Figs. 6 and 10, said

plates serving also to carry the reversed scale-plate W. As shown in said figures, each plate comprises two parallel leaves or arms V⁴ and V⁵ and an upturned lip V³ and is furnished at its forward end with an elongated hole or slot V⁶ to receive a fastening-screw V².

Each shield-plate V is carried by a block U, said blocks encircling the rod R² and being clamped at any desired point thereon by means of a set-screw U², Fig. 11.

The lips V³ serve to prevent the front pulleys S² on rod R² from moving laterally out of line with the arms or leaves V⁴, which latter pass beneath and protect the carrying-bands S.

The arms V⁵ serve to support the reversed scale-plate W, which may be accurately adjusted through proper setting of the blocks U, and by reason of the slotting of the ends 20 of the shield-plates V to receive the fastening-screws V².

D, Figs. 2 and 9, indicates a shaft or axle carried in suitable bearings, one of which is in the hanger A², and secured upon this shaft 25 is a worm-wheel E.

E² indicates a worm or screw meshing with the wheel E and serving to rotate said wheel or to hold it against rotation, as required, said worm or screw being carried by a shaft 30 mounted in a suitable sleeve or bearing and provided with a small crank or handle by which to turn it.

D² indicates a cam or scroll shaped drum, shell, or casing loosely placed upon shaft D, 35 but connected therewith through the medium of an interposed coiled spring D³, one end of which is made fast to the shell and the other to the shaft. The purpose of the spring is to turn the shell or casing in one direction 40 and to cause a strap or band T to wind upon its exterior cam-surface, the band having one end attached to the outermost point of the cam or scroll, as indicated in Fig. 8. The other end of the band T is attached to carriage L. Hence as the spring turns the drum or shell D² the carriage is drawn forward in 45 the direction necessary for letter-spacing. The tension of spring D³ may be varied by turning the worm or screw E² and thereby 50 rotating worm-wheel E and shaft D.

When the spring is coiled to the greatest extent which it attains, the point or extremity of the scroll or cam drum D² is at such elevation that the band T is free from its periphery, 55 or nearly so; but as the shell or drum D² turns the band winds upon its periphery and approaches nearer and nearer to the axis of rotation. It will be seen that by reason of this arrangement the leverage of the shell is 60 least when the tension of the spring is greatest and greatest when the tension of the spring is least. Hence the pull of the spring as exerted upon the carriage is uniform throughout and the stroke required to actuate 65 the spacing-dogs is the same throughout the travel of the carriage. This is a feature of great importance, because if the force re-

quired to operate the letter-space dogs and consequently the finger-key levers varies the impression will be irregular, the wear will be 70 uneven, and the speed of operation will be materially lessened.

By turning the worm E² in one or the other direction the tension of spring D³ may be 75 varied as desired.

Loosely mounted upon the shaft or axle D by the side of shell or drum D² is a combined ratchet-wheel and bevel-pinion, (shown in Figs. 8 and 9,) through which latter motion is given to a second bevel-pinion secured upon 80 a shaft H, carried in suitable bearings at the rear side of the machine below the top plate.

The shell D² carries a spring-pressed pawl which engages with the ratchet-wheel when the shell turns to advance the carriage, but 85 which rides back over the teeth of the ratchet when the rotation is reversed in receding the carriage.

Shaft H is capable of longitudinal adjustment and is provided with means for holding 90 it at any desired adjustment. The pinion through which it is rotated is fixed against movement other than rotation, the shaft H sliding through it when being adjusted. Upon shaft H are two other bevel-pinions, so 95 located that when the shaft is at either extreme of its longitudinal movement one or the other of said pinions shall mesh with a like pinion on one or the other of two ribbon-spool shafts H² H², extending horizontally beneath the top plate of frame A, perpendicular to shaft H.

The shafts H² are carried in suitable bearings and are grooved longitudinally, as shown in Fig. 9. Each shaft H² carries a ribbon-spool I, having a spur or feather to enter the groove thereof, whereby the spool is caused to rotate with, but is permitted to slide upon, the shaft, which is made of adequate length for the purpose.

J indicates an oscillating frame comprising a horizontal rock-shaft and two upright arms, as shown in Fig. 1, said shaft being journaled or carried in bearings in the main frame and the upper ends of the arms being shouldered 115 and carried through perforations in slotted slides J², held beneath the top plate of the frame by guide-screws or like means. Each slide J² carries a bent-wire yoke K K² of the form illustrated in Figs. 1 and 9—that is to 120 say, it comprises a depending loop K at each end of the spool and bearing lightly against the same and a raised cross-bar K² above the spool and serving as a guide and support for the inking-ribbon, which passes up over the 125 cross-bars of the two guides and is stretched between them close beneath the platen or paper roll. The two slides J², being connected through the oscillating frame J, move in unison. Hence if either spool be moved 130 along its shaft the other will be simultaneously and equally moved and thus the ribbon will be caused to travel in a straight line parallel with the front of the machine.

The key-levers C are furnished with finger-buttons C², as usual.

I claim—

1. In a type-writing machine, the combination of a paper-carriage; a spring drum or barrel having a cam or snail-shaped surface; a flexible band attached to the carriage and arranged to wind upon the snail-shaped surface of the drum; printing devices; spacing mechanism for holding and releasing the carriage to permit a step-by-step advance; and a series of finger-key levers serving to actuate the printing devices and to control the spacing mechanism; whereby the power required to depress the finger-key levers, to control the spacing mechanism and to give a proper printing impression is maintained uniform throughout the travel of the carriage.

2. In a type-writing machine, the combination of an inking-ribbon; ribbon-spools adapted to turn upon their axes and to move longitudinally thereof; guides adapted to embrace and to hold in place the ribbon-spools and ribbon; and a movable frame connected with said guides and serving to effect a simultaneous and equal movement of both spools.

3. In a type-writing machine, the combination of a supporting bed or plate; a carriage L, movable in a line parallel with the front of the machine; rollers M carried by the end bars of the frame of said carriage; and a supplemental frame provided with a platen Q and having its end bars N supported upon the rollers M of the primary carriage, substantially as described and shown.

4. In a type-writing machine, the combination of a primary paper-carriage, adapted to move in the direction of the printing-line; a secondary paper-carriage carried by the primary carriage and movable over the same at right angles to the printing-lines; stops to limit the movements of the supplemental carriage; and hooks to engage said stops and hold the supplemental carriage in its adjusted positions.

5. In combination with the primary carriage having stops M² M²; a supplemental carriage; a rocking block O³, mounted upon the supplemental carriage; and provided with studs O⁴; and hooks O pivotally attached to the block O³ and adapted to engage alternately with the stops M² M².

6. In combination with carriage L, supplemental carriage N N, R²; rocking blocks O³ carried by the supplemental carriage and provided with hooks O and studs O⁴; rod P connecting the blocks O³ and provided with guide-bar P'; rod P² and yoke P³ carried by bar P'; rod P⁴ fitting within the yoke P³; elbow-levers P⁵ supporting the rod P⁴; and finger-keys connected with and serving to rock said levers, substantially as set forth.

7. In a type-writing machine, the combination of a platen shiftable at right angles to the printing-line, and means for locking said platen in its normal position.

8. In a type-writing machine, the combination of a platen shiftable at right angles to the printing-line, and means for locking said platen in its shifted position.

9. In a type-writing machine, the combination of a platen shiftable at right angles to the printing-line; means for locking said platen in its normal position; and means for locking the platen in its shifted position.

10. In a type-writing machine, the combination of a platen shiftable at right angles to the printing-line; a vibratory shifter-bar parallel with the platen; connections between the platen and shifter-bar; a shift-key lever at the keyboard; and connections between the shifter-bar and the shift-key lever.

11. In a type-writing machine, the combination of a primary paper-carriage movable in the direction of the printing-line; a secondary carriage supported by the primary carriage and movable thereon at right angles to the printing-line; a vibratory shifter-bar parallel with the printing-line; a crotch or yoke carried by the secondary carriage and arranged to straddle the shifter-bar; and a shift-key connected with the shifter-bar and serving to move the same laterally.

12. In a type-writing machine, the combination of a longitudinally-traveling platen capable also of transverse movement; a shifter-bar extending parallel with the platen; and a finger-key connected with the shifter-bar and serving to shift it and the platen transversely at any and all points in the travel of the platen.

13. In a type-writing machine, the combination of a longitudinally-traveling platen; and a transversely-movable shifter-bar parallel therewith and mounted in the frame of the machine, and so connected with the platen as to shift the same transversely or at right angles to its axis, at any and all points in the travel of the carriage.

14. In a type-writing machine, the combination of a longitudinally-traveling platen, and a shifter-bar at least as long as the travel of the platen, mounted in the main frame, and so connected to the platen as to shift the same transversely to its axis at any and all points in the travel of the platen.

15. In a type-writing machine, the combination of a longitudinally-traveling platen; a shifter-bar connected with the platen and serving to shift the same transversely; and rocker-arms for carrying said shifter-bar.

16. In a type-writing machine, the combination of a longitudinally-traveling platen; a shifter-bar connected with the platen and serving to shift the same transversely; rocker-arms for carrying the shifter-bar; and a key-lever for moving the shifter-bar.

WILLIAM K. JENNE.
